(57) **CLAIM**

The ornamental design for a facial interface assembly for head-mounted display as shown and described.

DESCRIPTION

FIG. 1 is a front perspective view of a facial interface assembly for head-mounted display, showing a new design; FIG. 2 is a front view of the facial interface assembly of FIG. 1;

FIG. 3 is a rear view of the facial interface assembly of FIG. 1;

FIG. 4 is a left side view of the facial interface assembly of FIG. 1;

FIG. 5 is a right side view of the facial interface assembly of FIG. 1;

FIG. 6 is a top view of the facial interface assembly of FIG. 1;

FIG. 7 is a bottom view of the facial interface assembly of FIG. 1; and,

FIG. 8 is a bottom perspective view of the facial interface assembly of FIG. 1.

The broken lines are for the purpose of illustrating portions of the facial interface assembly that form no part of the claimed design.

1 Claim, 8 Drawing Sheets
